Geo. Storke.

ATTORNEY.

UNITED STATES PATENT OFFICE.

ALBIN B. GUSTAFSON, OF DULUTH, MINNESOTA.

DIRECTION-INDICATOR FOR VEHICLES.

1,236,707.

Specification of Letters Patent. Patented Aug. 14, 1917.

Application filed December 26, 1916. Serial No. 136,915.

To all whom it may concern:

Be it known that I, ALBIN B. GUSTAFSON, a citizen of the United States, residing at Duluth, in the county of St. Louis and State 5 of Minnesota, have invented certain new and useful Improvements in Direction-Indicators for Vehicles, of which the following is a specification, reference being had therein to the accompanying drawing.

10 This invention relates to direction indicators for vehicles such as automobiles or the like, and has special reference to the particular form of indicator and mechanism for operating same.

15 The principal object is to produce a device of this character of simple construction and one in which the danger of becoming inoperative by the action of inclement weather is reduced to a minimum.

20 Other objects and advantages will appear from the further description of the device.

In the accompanying drawings forming part of this application and in which like reference characters indicate like parts:

25 Figure 1 is a longitudinal vertical sectional view partly in elevation of my improved indicator.

Fig. 2 is a transverse sectional view on the line A—B, Fig. 1, looking rearwardly.

30 Fig. 3 is a front elevation of the indicator, and

Fig. 4 is a diagrammatic view of the electrical controlling mechanism.

1 represents a cylindrical shaped indicator housing upon the rear end of which, 35 mounted in any desired manner, the convex cap 2 and the opposite end having the usual glass 3 and reflector 4 carried in similar lights. Upon the front end of the housing 1 is formed integral therewith a hollow up- 40 standing extension 5, which carries upon its uppermost front face an electric globe 6 of somewhat similar form to the globe 7 within the reflector 4 though preferably of less 45 brilliancy and which globe may, as desired, be of a different color to that of the globe 7. The entire indicator is revolvably carried upon a hollow shaft 8 supported in any desired manner upon the vehicle.

50 The bearings upon the shaft which support the light comprise the transverse plate 9 soldered or fixed in any desired manner to the inner opposite side walls of the body 1, the vertical plate 10 shown as fixed to the 55 walls of the body by means of suitable rivets

11 which also unites the cap 2 to the body, and the hub like extension 12 upon the cap 2.

The indicator body is held longitudinally upon the shaft 8 by an annular shoulder being formed upon the latter as at 12' and against which the plate 10 normally abuts, the shaft forward of said plate being smaller in diameter than that at the rear thereof and which smaller portion 13 extends through the plate 9 and is held therein by a suitable cotter pin 14. Suitable frictional condition between the indicator and the shaft to prevent its loosely and undesirably revolving upon the shaft is accomplished by means of an expansive spiral spring 15 placed about the shaft 8 intermediate of a suitable set collar 16 fixed to the shaft and the plate 10, said spring maintaining at all times a slight thrust upon the plate 10 to produce the desired frictional contact and it is evident that the set collar may be adjusted longitudinally of the shaft to vary this frictional contact as desired.

Upon the portion 13 of the shaft 8 and intermediate of the plates 9 and 10 is securely fixed as by suitable set screws 17 an upwardly extending radial arm 18, having formed integral therewith a round semi-circular shaped solenoid core formed concentrically with the indicator body.

Within the lower half of the indicator body and formed concentrically therewith are two quadricircular solenoids 20 and 21, they being supported in any desired manner to the inner wall of the indicator and plate 10, as for example, by soldering at the ends thereof. These solenoids are positioned in proper circular alinement with the two halves of the core 19 in such a manner that the latter is influenced by the electric energy of the former and that alternately to accomplish the desired results. The wire connections to the solenoids are not shown other than in the diagrammatic view as they may be concealed or formed in various ways, but are made through the hollow shaft 8 similar to the other electric connections.

All of the wiring to the indicator will preferably pass through a suitable opening as at 22 to the interior of the shaft 8 and extend through the extreme inner end thereof to the globes 6 and 7 and to the solenoids. A hollow offset portion 23 is formed at the base of the rear wall of the extension 5 in such a manner as to produce

a suitable conduit for the wires leading to the globe 6. In the bottom of the indicator housing may be placed any desired form of counter weight 24 to properly balance the indicator upon the shaft and cause it to remain normally with the globe 6 in vertical alinement with the globe 7, as is obvious.

In a practical application of my device to a vehicle as illustrated in Fig. 5, a plurality of indicators may be employed as for example, one in the center of the car forward, one in the rear and one or more at the sides, as desired; it being possible that one at the forward end and one at the rear end may answer every practical purpose, they being operated simultaneously by a suitable switch 25 located in any desirable accessible position to the operator of the vehicle. The electric energy may be derived from a battery or other source as desired and which is indicated at 26.

The operation of the device is as follows, when it is desired to operate the indicator in a clockwise direction, viewing it from the face, the switch 25 is thrown to contact position with the point 27 which will close the circuit in the wires passing around the solenoid 20. This will tend to draw that portion of the core 19 designed to cooperate therewith within said solenoid, but the core being held stationary by being fixed to the shaft, the solenoid itself will be obliged to respond to the drawing influence and be carried longitudinally the core, thus carrying with it the body of the indicator, it being attached thereto and which will rock the arm 5 in a clockwise direction. When the switch is returned to its original position and the circuit opened, the counter balance of the indicator will return it to normal vertical position.

When desired to operate the indicator in an anti-clockwise direction, the switch 25 is thrown to engage the contact point 28 which will close the circuit through the

solenoid 21 and correspondingly operate the indicator in the direction opposite to that first described.

From the foregoing it is evident that I have devised a simple form of revoluble direction indicator, which may be illuminated at night and made of a suitable color to be readily seen in the day time and that sleet, rain or snow can not well interfere with the successful operation of the device.

Having thus described my invention what I claim and desire to secure by Letters Patent, is:

1. A direction indicator for vehicles comprising a horizontally disposed shaft supported by the vehicle, a revoluble housing carried by the shaft, a normally upstanding extension upon the forward end of the housing, a light carried in the housing, a light carried in the upper end of the extension electrically controlled, means within the housing for rocking the same in either direction and means for normally maintaining the housing in a position in which the extension is disposed vertically above the center of the housing.

2. An indicator for vehicles, comprising a fixed shaft, a cylindrical housing revolably carried by the shaft, a direction indicator extending radially from the housing and carrying a light, a light located centrally within the forward end of the housing, a pair of oppositely disposed quadrangular shaped cylindrical solenoids fixed within the housing, a core fixed to the shaft and designed to co-operate with the solenoids and means whereby the solenoids are separately energized.

In testimony whereof I hereunto affix my signature in the presence of two witnesses.

ALBIN B. GUSTAFSON.
